DIAGNOSTIC INSTRUMENT

Original Filed Feb. 15, 1923

Patented Mar. 15, 1927.

UNITED STATES PATENT OFFICE.

HENRY L. DE ZENG, OF GENEVA, NEW YORK, ASSIGNOR TO AMERICAN OPTICAL COMPANY, OF SOUTHBRIDGE, MASSACHUSETTS, A VOLUNTARY ASSOCIATION OF MASSACHUSETTS.

DIAGNOSTIC INSTRUMENT.

REISSUED

Original application filed February 15, 1923, Serial No. 619,085. Divided and this application filed October 3, 1925. Serial No. 60,215.

This invention relates to improvements in diagnostic instruments, and has particular reference to hand operated instruments, such as ophthalmoscopes, retinoscopes, otoscopes, etc., adapted to project a beam of light for the purpose of making examinations of the eye.

This application is a division of my co-pending application filed February 15, 1923, Serial Number 619,085, now Patent No. 1,559,558, dated November 3, 1925.

One of the principal objects of the present invention is to provide an electric diagnostic instrument wherein new and novel means are provided for controlling the lamp circuit.

A still further object is to provide an electric diagnostic instrument wherein the lamp controlling means is so constructed and arranged that when the operator desires to use the instrument he can open or close the circuit through the lamp as may be desired, by the use of a single hand which is employed in holding the instrument.

Another object is to provide an improved circuit breaker which is positive in its contact and which contains no delicate electrical connections which frequently become inoperative and troublesome.

Another object is to provide a circuit breaker which is very compact, symmetrical and not readily displaced from its position of contact.

A further object is to provide such a device which will be simple in its construction, strong and durable in service, and an advance in the art.

Other novel features of construction, together with additional advantages of the present invention, will hereinafter more fully appear in the following detailed description and the appended claims.

For the purpose of illustrating the present invention, there has been shown in the accompanying drawings, one embodiment which is at present to be preferred, since this embodiment will be found in practice to give satisfactory and reliable results. It is, however, to be understood that the various instrumentalities of which the invention consists can be variously arranged and organized, and that the invention is not to be construed as limited to the precise arrangement and organization of these instrumen-

talities, as hereinafter shown and described. 55

Figure 1 is a side view, partly in section, of a diagnostic instrument constructed in accordance with the present invention.

Figure 2 is an enlarged sectional view of the circuit controlling mechanism. 60

Figures 3 and 4 are perspective views of two different washers employed in the construction of the present invention.

Referring to the drawings, and particularly to Figure 1, there is shown a diagnostic instrument comprising a handle 10, at the upper end of which is an extension 11 adapted to support the body portion or instrument head 12. In this view an ophthalmoscope has been illustrated, but it is to be understood that the invention may be equally well applied to retinoscopes, otoscopes, etc. 65

Referring to Figure 2, it will be noted that the handle member 10 is hollow and adapted to contain an electrical battery 13, at the upper end of which is the usual pole 14. The said handle member 10 is closed at its lower end by means of a removable closure 15, and is provided at its opposite end with the cover 16, having a central opening therein, and within which opening is arranged to be secured in any suitable manner, such as by means of a press fit, an insulating ring 17 formed with an outwardly projecting bead 18. Positioned between the said bead 18 and the cover 16 is a metal washer 19, such as shown in Figure 4. 70 75 80 85

Also secured within the opening of the cover 16, but inwardly of the ring 17, is a lamp holder 20, which is centrally apertured and screw-threaded to form a socket 21 for the reception of an incandescent lamp 22. Below the socket 21 the holder is bored out to a larger diameter, as at 23, and secured within this bore is an insulating bushing 24, 90 95 said bushing being formed with a recess 25, within which is positioned a plunger 26, which projects through the opening 27 in said bushing and is urged into contact with the lamp 22 by means of a spring 28 which is held within said recess by means of the threaded cap 29. The cap 29 is also provided with a recess 30, to receive the lower end portion of the spring 28, whereby to retain the same in proper contact with the plunger 26. 100 105

Formed integrally with and adjacent the socket end of the lamp holder 20 is the collar 31 and adjustably threaded upon and

surrounding said holder 20, between the collar 31 and insulating member 17, is a sleeve 32 provided at its lower end with the depending flange 33 adapted to contact with the washer 19 in order to close the circuit through the lamp, as will be more fully hereinafter set forth. Surrounding the lamp holder 20, and positioned between the shoulder 31 and sleeve 32, is a friction washer 34, such as shown in Figure 3, the collar 31 acting as a stop to limit the upward movement of the sleeve.

Secured to the inner face of the closure 15, and contacting with the bottom of the electrical battery 13, is a coil spring 35, which urges the battery in the direction of the lamp, whereby to retain the pole 14 in contact with the cap 29.

Threaded upon the upper end of the lamp holder 20 is a detachable member 36 having a bore or passage 37 therethrough, at the bottom of which is located a translucent member 38, while at the top of the passage is located the condensing lens 39. Threaded upon the upper end of the detachable member is the casing 40, having the passage 41 therein, at the outer portion of which is located the condensing lens 42, the elements 38, 39 and 42 being in vertical alignment.

The upper end portion of the casing 40 carries the housing 43, within which is contained the rotatable disk 44 having ports 45 which can be turned into alignment with the port 46 of the stationary member 47. The outer wall of the casing 43 has the slot 48 therein, which is in horizontal alignment with the ports 45 and 46 and the slot 50 in the casing. Located above the condensing lens 42 is a reflector 48, having the sight opening 49 which is in alignment with the said ports 45, 46 and the slots 48 and 50 the reflector directing the light at approximately right angles to the optical axis of the lens 42, the operator viewing the eye of the patient through the slot 48.

The operation of the present invention and particularly the circuit controlling mechanism is as follows: When it is desired to close the circuit through the lamp, the sleeve 32 is rotated in the proper direction until the flange 33 thereof contacts with the washer 19. The electric current will then flow from the battery through the cap 29, the spring 28 and plunger 26 into the lamp 22. The current then flowing through the lamp, and back into the battery 13, will pass through the holder 20 into the sleeve 32, from the said sleeve 32 through the washer 19 into the handle member 10 and thence through the spring 35 back into the battery 13. When it is desired to break the circuit it is only necessary to rotate the sleeve 32 in the opposite direction until the flange 65 thereof no longer contacts with the washer 19.

It will be readily apparent from the above that there has been devised a new and useful diagnostic instrument which embodies the features of advantage enumerated as desirable in the statement of the invention and the above description and while there has, in the present instance, been shown one practical embodiment which will in practice, give satisfactory and reliable results, it is to be understood that this invention 75 is susceptible to modifications in various particulars without departing from the spirit or scope of the invention or sacrificing any of its advantages. For instance, either one or both of the washers 19 and 34 may be 80 eliminated if desired without affecting the practicability of the instrument in any way inasmuch as the washer 34 is simply a friction washer employed to prevent the sleeve 32 from accidentally rotating and closing 85 the circuit, while should the washer 19 be removed, the flange 33 of the sleeve 32 would contact directly with the cover 16 of the handle member, which contact would effectively close the circuit through the lamp. 90

It is in view of such modifications as referred to above that the invention is not to be construed as limited to the precise details of construction herein shown and described but instead, that the right is reserved to make any such changes as properly fall within the scope of the appended claims without departing from the spirit of the invention. 95

What is claimed is:

1. In a device of the character described, a handle, a battery in the handle having a projecting pole member, a cover cap over the handle having an internal opening, an annular lamp socket in the opening of the cap, an annular insulating member on the inside of the lamp socket, an annular insulating member on the outside of the lamp socket insulating the same from the cap, a contact member in the inner insulating member connecting with the lamp socket and adapted to engage the battery pole, a contact piece on the cap insulated from the light socket and an annular sleeve rotatably mounted on the outside of the lamp socket 105 having a portion adapted to engage the contact piece on the cap in certain rotative positions to close the circuit and to disengage the contact in other positions to break the circuit. 110

2. In a device of the character described, a handle, a battery in the handle having a projecting pole member, a cover cap over the handle having an internal opening, an annular lamp socket in the opening of the cap, an annular insulating member on the inside of the lamp socket, an annular insulating member on the outside of the lamp socket insulating the same from the cap, a contact member in the inner insulation con- 120

necting with the lamp socket and adapted to engage the battery pole, a contact piece on the cap insulated from the light socket, an annular sleeve rotatably mounted on the 5 outside of the lamp socket having a portion adapted to engage the contact piece on the cap in certain rotative positions to close the

circuit and to disengage the contact in other positions to break the circuit, a member having a light passage way over the lamp 10 socket and means for detachably connecting the lamp socket to the light passage way member.

HENRY L. DE ZENG.
